OCARINA

George A. Mausolf, Waterbury, Conn., assignor to
The Waterbury Button Company, Waterbury,
Conn., a corporation of Connecticut

Application May 6, 1939, Serial No. 272,166

10 Claims.

(CL 84—330)

This invention relates to musical instruments, and more particularly to improvements in ocarinas.

One object of this invention is to provide an improved form of ocarina constructed of two halves sealed together at their abutting edges and which are molded from a plastic compound, such as Bakelite, cellulose acetate, etc.

A further object is to provide an ocarina of the above nature in which the mouthpiece is formed entirely of plastic compound similar to that from which the body of the ocarina is molded.

A further object is to provide an ocarina of the above nature which will be simple in construction, inexpensive to manufacture, readily manipulated, compact, ornamental in appearance, and very efficient and durable in use.

With these and other objects in view, which will appear as the description proceeds, there have been illustrated in the accompanying drawing several forms in which the invention may be conveniently embodied in practice.

In the drawing:

Fig. 1 is a perspective view of an ocarina embodying the first form of this invention.

Fig. 2 is a broken interior plan view of one of the molded halves of the first form of ocarina shown in Fig. 1.

Fig. 3 is a broken plan view of the other molded half of the same ocarina, looking at its interior surface.

Fig. 4 is an enlarged longitudinal sectional view of the mouthpiece of the same, taken on the line 4—4 of Fig. 1.

Fig. 5 is a transverse sectional view of said mouthpiece taken on the line 5—5 of Fig. 4.

Fig. 6 is an interior plan view of the mouthpiece end of a modified form of ocarina.

Fig. 7 is a sectional view of the same, taken on the line 7—7 of Fig. 6.

Fig. 8 is a broken interior plan view of the mouthpiece end of another modified form of ocarina.

Fig. 9 is a transverse sectional view taken on the line 9—9 of Fig. 8.

Referring now to the drawing wherein like reference characters designate like parts throughout the several views, the numerals 10 and 11 denote the top and bottom hollow molded halves respectively of the improved ocarina of this invention. The top half 10 is provided with a semi-tubular mouthpiece portion 12, and an oval-shaped body portion 13 having a plurality (in this instance eight) of finger openings 14

which are adapted to be covered by the fingers of the user's hands. The openings 14 are each surrounded by ribs 15 which are raised from the exterior surface of the body portion 13. The bottom half 11 is provided with a semi-tubular 5 mouthpiece 16 and an oval-shaped body portion 17, having two openings 18 adapted to be covered by the thumbs of the user's hands, and an enlarged outlet opening 19. The openings 18 are each surrounded by a rib 20 which is raised from the exterior surface of the body portion 17. The outlet opening 19 has no raised rib and the outer surface of the body 17 is countersunk around it. In order to cause the two halves 10 and 11 to tightly interfit, the outer edges of 10 the curved walls of the body portions 13 and 17 and the side edges of the mouthpieces 12 and 16 are formed flat to permit them to be sealed in tight abutment. A flange 21 is provided on the flat edge of the top half 10, which flange 21 fits 20 within a cooperating groove 21a in the bottom half 11.

The mouthpiece 16 of the bottom half 11 is provided with a longitudinal groove 22 which extends from the outer end 23 of the mouthpiece 16 to the outlet opening 19, to cause air blown into the mouthpiece to traverse said outlet opening and produce a musical note, the tone of which may be varied by the covering and uncovering of the various finger and thumb openings 14 and 18, 30 while playing the ocarina in the usual manner. The bottom 24 of the groove 22 is inclined rearwardly and outwardly away from the abutting edges at the outer end 23 between the halves 10 and 11, and is preferably slightly concave both 35 longitudinally and transversely. The sides of the groove 22 also converge slightly from the outer end 23 of the mouthpiece 16 toward the outlet opening 19—being smaller in width adjacent said opening.

In order to form an enclosed air-blowing passage in cooperation with the groove 22, provision is made of a tapered longitudinal solid rib 25, which in this instance is formed integral with the mouthpiece portion 12 of the top half 10. The rib 25 is made substantially wedge-shaped, increasing gradually in thickness from the outer to the inner ends of the mouthpiece. The sides of the rib 25 are adapted to fit snugly in the sides of the groove 22 (see Fig. 5).

In the modified form of mouthpiece 26 shown in Figs. 6 and 7, the top half 27 is provided with a tapered hollow rib 28 formed integral with the top mouthpiece portion and having an exterior longitudinal slot 29 formed therein during the 55

molding of said top half 27. The inner narrow end of the hollow rib 28 is closed by a wall 30. By means of this construction, the forming of the top half 27 by hot molding is facilitated since the thin walls of the rib 28 permit the rapid and uniform "curing" of the plastic material being molded. A further advantage of this construction is that it results in a substantial reduction in the weight of the ocarina.

10 In the modified form of ocarina shown in Figs. 8 and 9, a hollow rib or block 31 is provided which is U-shaped and formed separately from either half. The legs of the rib 31 are adapted to fit tightly in a tapered groove 32 formed between a pair of spaced-apart small ribs 33 and 34 formed integral with the top ocarina half 35. The inner ends of the small ribs 33 and 34 are inturned to provide stops 36 and 37 to hold the rib 31 in proper position. In other respects, the 15 rib 31 is similar to the integral solid rib 25 shown in the first form (Figs. 1-5). The interior hollow section 33 of the U-shaped rib 31 is adapted to be closed by end walls 39 and 40, side walls 41 and 42, and a top wall 43.

20 25 Among the advantages of the improved ocarina of this invention are the facts that it is extremely light in weight; it may be made of colored plastic material requiring no exterior coating of enamel, paint or the like; it has no metallic parts liable to corrode; and it has a smooth, non-chippable outer surface.

While there have been disclosed in this specification several forms in which the invention may be conveniently embodied in practice, it is to be understood that these forms are shown for the purpose of illustration only, and that the invention is not to be limited to the specific disclosures but may be modified and embodied in various other forms without departing from its 30 spirit. In short, the invention includes all the modifications and embodiments coming within the scope of the following claims.

Having thus fully described the invention, what is claimed as new and for which it is 45 desired to secure Letters Patent, is:

1. In an ocarina, a pair of interfitted complementary hollow halves, each half having a complementary mouthpiece portion, one of said mouthpiece portions having a longitudinal 50 groove formed therein, and the other mouthpiece portion having a longitudinal rib adapted to fit tightly within the sides of said groove and in slightly spaced relation from the opposing wall of said groove to provide an air blowing 55 passage.

2. In an ocarina, a pair of complementary hollow halves, each half having a complementary mouthpiece portion and a plurality of openings each surrounded by an exterior raised rib, one 60 of said halves having a main outlet opening therein, one of said mouthpiece portions having a longitudinal groove therein extending from the end of said portion to said main opening, and the other mouthpiece portion having a longitudinal rib fitting the sides of said groove and spaced from the bottom surface of said groove to form an air blowing passage therebetween.

3. In an ocarina, a pair of complementary hollow halves, each half having a complementary mouthpiece portion, one of said mouthpiece portions having a longitudinal groove therein and the other mouthpiece portion having a longitudinal rib adapted to fit tightly within the 70 sides of said groove and to be spaced from the

bottom thereof to form an air blowing passage therebetween, said rib being formed integral with said other mouthpiece portion and having a recess therein extending inwardly thereinto from the outer surface of said other mouthpiece portion.

4. In an ocarina, a pair of complementary hollow halves, each half having a complementary mouthpiece portion and a plurality of openings each surrounded by an exterior raised rib, one 10 of said halves having a main outlet opening therein, one of said mouthpiece portions having a longitudinal groove therein extending from the end of said portion to said main opening, and the other mouthpiece portion having a longitudinal rib fitting the sides of said groove and inclined with respect to the bottom surface of said groove to form a tapered converging air-blowing passage therebetween.

5. In an ocarina, a pair of complementary hollow halves, each half having a complementary mouthpiece portion, one of said mouthpiece portions having a longitudinal inclined groove therein, the other mouthpiece portion having a pair of small spaced raised ribs, a hollow inclined U-shaped block tightly fitted between said ribs and sealed to said mouthpiece, said block being spaced from the bottom surface of said groove to form an air-blowing passage.

6. In an ocarina, a pair of interfitted complementary hollow halves, each half having a complementary mouthpiece portion, one of said mouthpiece portions having a longitudinal groove formed therein, and the other mouthpiece portion having a longitudinal rib adapted to fit tightly within the sides of said groove and in slightly spaced relation from the opposing wall of said groove to provide an air-blowing passage, said rib being hollow.

7. In an ocarina, a pair of interfitted complementary hollow halves, each half having a complementary mouthpiece portion, one of said mouthpiece portions having a longitudinal tapered groove formed therein, and the other mouthpiece portion having a longitudinal tapered rib adapted to fit tightly within the sides of said groove and in slightly spaced relation from the opposing wall of said groove to provide an air-blowing passage.

8. In an ocarina, a pair of complementary hollow sections, each section having a complementary mouthpiece portion, a grooved block fitted between said mouthpiece portions, the space between said groove and the adjacent wall of said mouthpiece portion forming an air-blowing passage.

9. In an ocarina, a pair of complementary hollow halves, each half having a complementary mouthpiece portion, one of said mouthpiece portions having a longitudinal inclined groove 60 therein, the other mouthpiece portion having a pair of small spaced raised ribs, an inclined block tightly fitted between said ribs and sealed to said mouthpiece, said block being spaced from the bottom surface of said groove to form an air-blowing passage.

10. In an ocarina, a pair of complementary hollow halves, each half having a complementary mouthpiece portion, a block tightly sealed between said mouthpiece portions, one side of said block being spaced from the surface of the adjacent mouthpiece portion to form an air-blowing passage.
